UNITED STATES PATENT OFFICE.

FREDERICK G. SARGENT, OF WESTFORD, MASSACHUSETTS.

WIRELESS APPARATUS.

974,191.

Specification of Letters Patent.

Patented Nov. 1, 1910.

Application filed April 3, 1909. Serial No. 487,609.

To all whom it may concern:

Be it known that I, FREDERICK G. SARGENT, a citizen of the United States, residing at Westford, in the county of Middlesex 5 and State of Massachusetts, have invented a new and useful Wireless Apparatus, of which the following is a specification.

This invention relates to a system for the wireless transmission of energy, particularly 10 adapted for telephony and telegraphy.

The principal objects of the invention are to provide means whereby both transmission and reception of the Hertzian waves will be improved and facilitated; to provide means 15 whereby the waves will be transmitted in substantially true spherical waves so that there will be no interference between the waves produced by the same transmitting terminal or propagator; and to provide an 20 improved detector which can be operated without any cohering material and will be capable of delicate tuning and adjustment.

Further objects and advantages of the invention will appear hereinafter.

Reference is to be had to the accompanying drawings, in which—

Figure 1 is a diagrammatic view showing two sections constructed in accordance with the principles of this invention; Fig. 2 is a 30 diagrammatic view of one of the stations on an enlarged scale; and Fig. 3 is a view of a modification of the receiving antennæ.

It has been the custom generally to provide each station with an aerial which is 35 used both for receiving and sending. I find that in this way the full efficiency of either receiving or sending is not obtained and for the purpose of securing a higher degree of efficiency the sending station A is provided 40 with a sending or transmitting aerial 10 preferably having a spherical terminal 11, and with a receiving aerial 12 having a receiving terminal 13 preferably in the form of antennæ consisting of a plurality of bare 45 wires. The propagator 11 is preferably located at a higher altitude than the antennæ 13. The two aerials preferably are provided with insulation on their surfaces and outside of this is a covering of zinc or other 50 material to retard the transmission of the Hertzian waves therethrough so that the terminals will be more efficient. The receiving station B is equipped substantially in the same way, but in order to get a high 55 degree of efficiency the weight and resistance of the propagating aerial 10 at station B

including its terminal are substantially the same as those of the receiving aerial 12 at station A, and vice versa. This gives the same capacity to the receiving parts at one 60 station and the transmitting parts at the other.

In order that the waves transmitted from the sending aerial may be sent out in true spherical waves so that they will not interfere with each other, the terminals 11 are preferably made spherical, but the receiving terminals are shown in the form of spreading antennæ for more efficiently receiving the vibrations and transmitting them to the 70 detector. Fig. 2 shows how each one of these aerials is connected up. The transmitting aerial is connected with a transmitter 14 which is connected with a conductor 15 which is grounded and connected at its 75 opposite end with a terminal 16 on the detector 17. The opposite terminal 18 of the detector is connected directly with the aerial 12. Both terminals 16 and 18 are connected with a circuit 19 in which is a battery or the 80 like 20, an instrument 21 for receiving or sending, and a potentiometer 22 for regulating the voltage.

Between the two terminals 16 and 18 the detector is located. The terminal 18 is connected with a binding post or the like 23 to which is secured one end of a bare conducting wire 24 of any desired shape. The other end of this wire is connected with a screw 25 which is adapted to be turned to regulate 90 the tension of the wire. This wire therefore is freely suspended so that it will be capable of vibration, but it can be tuned by turning the screw 25. Bearing lightly on the surface of this wire, preferably the side surface, is a contact point 26 mounted on a spring 27 which is in turn mounted on a block 28. The vibration of this spring is regulated by a screw 29 carried by said block in an obvious manner. The spring is connected through a resistance 30 to the terminal 16. This resistance preferably is made so as to be capable of yielding to permit the block 28 to move back and forth in a direction parallel with the direction of the wire 95 24. For this purpose the block is mounted to slide in ways 31. It will be understood that the purpose of adjusting the contact point 26 is to secure an additional tuning and provide for securing the maximum efficiency under all conditions, and that the block on which this point is supported may 100 105 110

be stationary if desired as ordinarily sufficient tuning may be secured by the screw 25 alone. It is preferred, however, to employ both the screw 29 and the longitudinal adjustment of the contact point 26 in combination with the screw 25.

For the purpose of restricting the vibration of the wire 24 a damper 32 may be used consisting of a spring regulated by a screw 33. This is placed so as not to interfere with the adjustment of the contact point 26.

I have found in practice that there is a slight tendency of the contact point 26 to cohere permanently to the wire. In order to prevent this a very light spring 34 of non-conducting material (even paper being used with success) is placed on the spring 27 so as to project beyond the contact 26 and strike the wire before the contact point.

20 In Fig. 3 is shown a modification of the antennae of the receiving aerial shown in the form of a series of parallel wires 35 supported by masts 36 and connected with the aerial.

25 While I have illustrated and described a preferred embodiment of the invention I am aware that many modifications can be made therein by any person skilled in the art without departing from the scope of the invention as expressed in the claims. Therefore I do not wish to be limited to all the details of construction shown and described, but

What I do claim is:—

1. In a device of the character described, 35 the combination of a metallic conductor supported at its ends and free to vibrate, and a vibratory carbon contact point adapted to engage said conductor, said contact point and conductor being adapted to vibrate under the influence of Hertzian waves.

2. A detector for the purpose described, comprising a conductor supported at two points and free to vibrate between said points, a conducting point adapted to engage said conductor and free to vibrate, and means for adjusting said point to and from the conductor, said contact point being movable along the conductor.

3. A detector for the purpose described, 50 comprising a conductor supported at two points and free to vibrate between said points, and a contact point lightly engaging it and adjustable along the conductor and transversely thereto.

55 4. A detector for the purpose described comprising a conductor supported at two points and free to vibrate between said points, and a vibratory contact point lightly engaging it between said two points, said conductor and contact point being connected with a circuit.

60 5. A detector comprising a conductor, a

yieldingly supported vibratory contact point 65 adapted to engage the side thereof, and a light non-conducting spring supported to vibrate with said contact point, and projecting beyond said point, whereby said light spring will engage the conductor before the 70 point to prevent permanent coherence.

6. A detector for wireless apparatus comprising a wire supported at its ends and adapted to vibrate under the influence of Hertzian waves, and a vibratory contact 75 point adapted to engage said conductor between its ends, the conductor and contact point each having a terminal constituting the terminals of a circuit, and means for preventing permanent coherence between 80 the conductor and contact point.

7. A detector for the purpose described comprising a conductor supported at two points and free to vibrate between said points, a contact point lightly engaging it, 85 and a damping device engaging the conductor to restrict the vibration.

8. A detector for the purpose described, comprising a conductor secured at its ends and free to vibrate, a conducting point 90 adapted to engage said conductor and free to vibrate, means for adjusting said point to and from the conductor, said contact point being movable along the conductor, and a damping spring adapted to engage 95 the conductor to restrict its vibrations.

9. A detector for wireless apparatus comprising a wire supported at its ends and adapted to vibrate under the influence of Hertzian waves, a contact point adapted to 100 engage said conductor, the conductor and contact point each having a terminal constituting the terminals of a circuit, and an adjustable damping spring adapted to engage 105 said conductor to restrict the vibrations thereof.

10. A detector comprising a conductor and a yieldingly supported vibratory contact point adapted to engage the side thereof, and a yielding non-conducting member 110 connected with said contact point and adapted to engage said conductor to decohere the detector.

11. A detector comprising a vibratory conductor and a yieldingly supported vibratory contact point adapted to engage the side thereof, and means for decohering the 115 detector.

In testimony whereof I have hereunto set my hand, in the presence of two subscribing 120 witnesses.

FREDERICK G. SARGENT.
